P. Cooper,

Steam-Boiler Fire-Box.

Patented Oct. 13, 1831.

Oct. 13, 1831

299

Peter Cooper
Patentee
Patent No. 1000

Cooper

The defendant agrees to in these present Patent and making part of the same containing a description in the words of himself Peter Cooper herein all of his improvement in the construction of Steam Boilers.

Know all men by these presents, That I Peter Cooper of the City and State of New York have invented a new and useful improvement in the art of constructing Boilers for the purpose of generating steam which I have named "Cooper's Steam Boiler" and that the following is a full and exact description of the construction and operation of the said improvement as invented by me. The Boiler in this improvement that I have invented is composed of two upright cylinders (plate 1 fig. 1) A and B, placed one directly above the other but not in contact of equal dimensions but different heights. Each of these is closed at the ends except as hereinafter described and they are connected together and a communication established between their upper ends by a small cylinder or pipe C, having the same proportionality as with the larger cylinders and of such length and diameter as the upper and lower parts of the two larger cylinders may require. The top of the cylinder A is all for the sake of convenience "the upper chamber" and the lower to "the lower chamber of the Boiler". Within the lower chamber B, there is a concentric cylinder D, closed likewise at the ends except as hereafter described, between whose outer cylindrical walls and the inside of the lower chamber there is a space D, of two inches more or less all round according to circumstances, and the bottom of which is three inches from the bottom of the lower chamber. This inner cylinder forms the furnace and is so situated, the bottom of the furnace is supported on the bottom of the lower chamber by tubes a, a, a, a, of about one inch in diameter at the top and one inch and a quarter at the bottom in the chase and on a number proportioned to the size of the bottom of the furnace and forming a communication between the inside of the furnace and the inside of the lower chamber or all hole E. The tubes a, a, a, a, are inserted into the cylinder D, and through them air

current of air introduced into the fire. The increased size of the air bottom is to prevent the possibility of the being choked up with cinders. The top of the furnace is connected with the upper end of the lower chamber by similar tubes b, b, b, b, of about three quarters of an inch in diameter, through which the draft of the furnace carries the heated air through and out by which the draft of the furnace carries the heated air through and out into the open space C, between the upper and lower chambers. Then the top of the furnace there is a projecting pipe or small cylinder E, of the same size with that which supports the upper chamber and closed at the top intended to increase the surface of air open by the heat. The top and bottom of the upper chamber are fastened together by a sufficient number of bolts c, c, c, c, and in the lower chamber the office of these bolts is performed by the tubes b, b, b, b, one broad tube apparatus there is a cylindrical covering, called the jacket K, K, K, K, the top of which rests upon the bolts made in the top of the upper chamber of the boiler and between the sides of which (the jacket) and the sides of the upper and lower chambers there is an open space all round of about an inch and three quarters I, I, I, I. The jacket is open at the bottom. The steam pipe connecting with the cylinder of the engine proceeds from the top of the upper chamber M. The door of the furnace N is in the side most convenient. In one side of the ash hole there is an opening O for the current of air to the fire. The water is supplied by means of a pipe P entering the lower chamber near the bottom. The upper and lower chambers besides being connected by the cylinder or pipe C, are further connected and preserved always in the same relative position by bars on their outer sides Q, R. The draft which is essential to this boiler is best produced by a fan, although other means may be used. When in operation the boiler is filled with water so that the upper chamber may be about one third full at P, R. The water is then in the lower chamber surrounding all the tubes at the bottom of the furnace a, a, a, a, through which the air is introduced and which is the office of the openings between the bars of a common grate and surrounding also the fire itself and the tubes above the furnace b, b, b, b, through which the heated air passes. The water is also in the tube between the two chambers and in the upper chamber to the height of one and a half at P, R. The fire being made, and sufficiently fed is

proposed on all accounts although coke or wood or limestone coal
may be used) the fire or other means used to create a strong draft from a
current of air into the air hole the door of which being shut the air passes
through the walls of the furnace and then passes highly heated through the
upper tube into the space between the upper and lower chamber where
being confined and prevented from spreading by the packed air spaces in
contact with the outside of the two chambers of the boiler still further heating
the water within and especially by the same draft that introduced it and
so out below the bottom of the furnace or by such other outlet as may be found
convenient. When this firebox is used for locomotive engines the smoke
and dust pass out under the carriage. By this arrangement the
greatest possible surface of water is exposed to the action of the fire, and the
steam generated is in proportion while the grate upon which the fire
is being fed is at all times in contact with water which may be
like the ordinary grate. The water to which is below the fire receives
that portion of the heat which has been given in the usual mode of construct-
ing boilers been entirely lost to the objects of the machine. The fire being
so perfectly in contact with the upper chamber no accident need be
apprehended from the water or it, sinking (through carelessness) be-
low the height here indicated. When a fire is used to produce the draft
it must be worked by hand until the steam is raised so high that it may
be worked by the machinery. In a locomotive engine when the fire is
full hot into the furnace the working wheel should be raised a little
from the rail which may be readily done by a screw or lever. Very little
steam will be sufficient then to move the machinery and along with it
the fire. By stopping the fire a damper is at once put upon the fire thus
losing no draft except what the fire produces and by changing the velocity
of the fire the degree of draft and the intensity of the heat may be regu-
lated at will. In the apparatus here described Volant is now and always
more convenient and serviceable as follows. The mode of constructing the bot-
tom of the furnace of parallel plates through which the air is introduced
by means of tubes to the fire and between which a constant supply
of water is kept exposed to the action of the fire, removing all the danger

since the surface upon which the fire rests from the destructive effects of intense heat. 4. B. Grates have been combination with tubes containing (eng) water. The fire however conveys the water into tubes which being driven out the tubes are liable to be burst in two, as the solid bars have been used the water getting to the fire an explosion would take place. In my invention the air is introduced through tubes and the volume of water is so great that there will always be sufficient for the feed intended. 2. I also claim as my own the separation of the boiler into two parts and the tubing of the lower one. 3. I also claim as my own the tube covering or jacket by which the smoke and dust are forced in a downward direction out under the bottom of the boiler or carriage. 4. And I claim as my own the combustion and form here described as preferable as well as no detail.
